UNITED STATES PATENT OFFICE.

FLOYD ELRAGE MONTGOMERY, OF CLARINDA, IOWA, ASSIGNOR OF ONE-HALF
TO JOHN S. SMITH, OF SAME PLACE.

CULTIVATOR.

SPECIFICATION forming part of Letters Patent No. 433,018, dated July 29, 1890.

Application filed April 16, 1890. Serial No. 348,230. (No model.)

To all whom it may concern:

Be it known that I, FLOYD ELRAGE MONTGOMERY, a citizen of the United States, residing at Clarinda, in the county of Page and State of Iowa, have invented a new and useful Cultivator, of which the following is a specification.

This invention relates to cultivators; and it has for its object to construct a machine of this class which shall possess superior advantages in point of simplicity, durability, and general efficiency.

With these ends in view the invention consists in the improved construction and arrangements of the detailed parts of the machine, which will be hereinafter fully described, and particularly pointed out in the claims.

In the drawings, Figure 1 is a perspective view of a cultivator embodying my improvements. Fig. 2 is a plan view of the same, certain parts having been shown in section for the purpose of illustrating the construction more clearly. Fig. 3 is a longitudinal sectional detail view taken on the plane indicated by the line $x-x$ in Fig. 1. Fig. 4 is a transverse sectional view taken on the line $y-y$ in Fig. 3. Fig. 5 is a detail sectional view taken through one of the frame-standards in rear of one of the arched connecting-bars. Fig. 6 is a perspective detail view of one of the parts or sections of one of the frame-standards. Fig. 7 is a perspective detail view of one of the cap-plates of said standards. Fig. 8 is a detail perspective view of one of the beam coupling-plates. Fig. 9 is a perspective detail view of one of the adjustable spindles. Fig. 10 is a detail sectional view taken on the line $z-z$ in Fig. 3. Fig. 11 is a perspective detail view showing an improved fender, which may be attached to the standards of the cultivator for the purpose of cultivating listed corn or the like. Fig. 12 is a perspective detail view of the seat or cap by means of which the tongue is connected to the cultivator.

Like numerals of reference indicate like parts in all the figures.

A complete cultivator embodying my improvements is provided with two separate standards or, as I term them, "movements," which in the drawings hereto annexed have

been designated by 11. These movements are constructed precisely alike, and each is composed of two separate parts or sections 22, one of which has been shown in detail in Fig. 6 of the drawings. The said parts 2 are each composed of the flat plate 3, provided at its lower end with an outwardly-diverging shoulder 4, from which a plate 5 extends in a downward direction. The plates 5 are provided with rearwardly-extending brackets 6, having means for the attachment of the cultivator-beams, as will be hereinafter more fully described. The portions 3 and 5 of the devices are provided on their outer sides with vertical strengthening-ribs 7. The plates 3, the inner sides of which are normally in contact with each other, are provided at their upper and near their lower ends with the semi-cylindrical flanges 8, the outer edges of which are provided with slots or notches 9.

The parts 22 of the movements or standards are connected by the coupling-caps, which are designated, respectively, by 10 and 11, and which engage the flanges 8 at the upper and lower ends of the plates 3. The said coupling-caps are provided with forward and rearward extending arms 12, which are connected by means of bolts 13, thereby serving to connect the parts 22 firmly and yet in such a manner as to permit the movement or standards to oscillate within the said coupling-caps, which latter are provided with flanges 14 to engage the flanges 8, as will be seen most clearly in Fig. 4 of the drawings.

The flanges 14 of the coupling-caps 10 and 11 are provided with inwardly-extending lugs 15 to engage the notches or slots 9, and thereby to limit the oscillating movement of the devices.

The downwardly-extending plates or parts 5 of the movement or standards are connected by means of a bolt 16, upon which a sleeve 17 is interposed between the said plates 5 to keep them the desired distance apart. A lug or key 18 serves to prevent the sleeve 17 from rotating upon the bolt. This sleeve is in the nature of a strain-block, and it must be made sufficiently strong and rigid to resist the pressure which is caused by the mounting of the spindle upon the bolt 16, as will be presently described.

The spindles, which are two in number, one for each movement, are designated by 19, and are of ordinary construction, being provided at their inner ends with collars or flanges 20 5 and at their outer ends with cap-nuts 21. Each of the spindles is provided at its inner end with an upwardly-extending arm or bracket 22, provided on its inner side with flanges 23 to engage the ribs 7 upon the outer side of the adjacent plate. The outer side of the arm or bracket 22 is provided with transverse teeth or corrugations 24, adapted to engage corresponding teeth or corrugations 25 in a block 26. The bolt 16 extends through a vertical slot 27 in the arm or bracket 22 of the spindle and through a perforation in the adjusting-block, when by tightening the nut upon the said bolt 16 the parts will be secured together very firmly and rigidly and at 20 any desired adjustment, which will be regulated by placing the spindle at any desired height. The block 25, it will be seen, is not capable of vertical adjustment, but only serves to retain the spindle at any adjustment at 25 which it may be placed. Said block is provided at its front edge with a vertical flange 28, the purpose of which will be hereinafter described.

The arms or brackets 12 of the coupling-caps 10 and 11 of each movement are provided in their meeting faces with notches or recesses, which, when the parts are placed together, form the slots 29. Said slots are for the reception of the ends of the arched or 35 curved guards 30, which form, practically, the arched axle of the cultivator. The ends of the said arched bars are provided with V-shaped notches 31, to be engaged by V-shaped lugs 32, formed in the inner sides or 40 ends of the slots 29, thereby serving to retain the arched axle-bars securely in position without possibility of displacement and without tightening any of the connecting-bolts to such an extent as to injure any of the parts connected thereby.

Between the rearward-extending arms or brackets 12 of the lower coupling-cap 11 of each movement is interposed an upward and rearward extending arm or bracket 33, 50 which is held securely upon the connecting-bolt 13, and which serves in practice for the suspension of the cultivator-beams when the latter are to be thrown temporarily out of operation, as will be seen in dotted lines in Fig. 55 1 of the drawings.

34 designates the draft-hooks, which are provided with rearward-extending arms designated, respectively, by 35 and 36, the former of which are provided at their rear ends with 60 perforations 37, whereby they are mounted upon the sleeves 17 on the bolts 16. The rear ends of the arms 36 are provided with hooks 38, which are hooked into slots 39, formed in the plates 5 near the lower ends of the latter. 65 It will be seen that by means of these draft-hooks the draft may be attached independently, as it were, to each movement. At the

same time the draft will in operation be perfectly equalized by mechanism forming part of my invention, and to be hereinafter more fully described.

40 40 designate arms or bars which are mounted upon the outer ends of the bolts 16, adjacent to the adjusting-blocks 26 and resting or bearing against the flanges 28 at the 75 front edges of the latter. Said arms 40 are provided at their outer ends with hooks 41, extending from the upper edges, and near their outer ends they are provided with transverse bolts 42.

43 designates extension-bars or drive-bars, which are provided with slots 44, by means of which they are mounted pivotally upon the bolts 42. The slots 44 admit of the longitudinal adjustment of the drive-bar 43, and the latter, when desired, may be folded upon the arms or brackets 40. These drive-bars serve in operation to some extent to support the axle and to aid the machine in passing obstructions. The spindles are to be provided with supporting-wheels 45 of ordinary construction.

The rearward-extending brackets 6 of the movement-standards are provided with annular bosses or flanges 46, surrounding perforations 47 therein. Said perforations 47 are provided near their front ends with lugs 48, and the brackets 6 are provided on their rear sides with eccentric lugs or teeth 49.

50 designates the cultivator-beams, which are provided at their front ends with vertical slots 51, in which are seated the coupling-plates 52, the upper and lower edges of which are provided with flanges 53 to bear against the upper and lower sides of the beams, and which are secured in position by means of the transverse bolts 54. The front ends of the coupling-plates 52 have forward-extending arms 55, which are connected by the vertical pins or bolts 56 to form clevises. These 110 clevises are connected with the draft-brackets 6 by means of the beam-coupling plates, one of which has been shown in detail in Fig. 8 of the drawings, and each of which is provided with a laterally-extending boss 56 to engage the flanges 46 of the draft-brackets. The bosses 56 of the plates, which latter are designated by 57, are provided with notches 58 to engage the lugs 48, formed in the perforations 47 of the draft-brackets. The coupling-plates 57 are provided with transverse 120 perforations 59 and 60, the former of which extends through the boss 56, and the latter of which extends transversely in rear of the latter. Consequently the coupling-bolt 61, which 125 passes through the perforation 60, will normally rest upon the eccentric lug or tooth 49 of the draft-bracket. The meeting faces of the coupling-plates are provided in their meeting faces, at their rear ends, with vertical 130 grooves 62, adapted to receive the vertical pins or bolts 56 of the clevises at the front ends of the cultivator-beams. It will thus be seen that by tightening the coupling-bolts 60

and 63 the parts may be firmly connected in such a manner as to permit the cultivator-beams to swing or oscillate both laterally and vertically, thus connecting the said cultivator-beams with their respective movements by practically universal joints. At the same time it will be observed that the movement in a downward direction of the cultivator-beams will be limited by the lugs 56 engaging the bolts 61 and by the notched bosses 56 engaging the lugs 48, as hereinbefore described.

The cultivator-beams are provided in the usual manner with standards 64, carrying shovels 65 of ordinary construction. Said beams are also provided with handles 67, by means of which they may be guided during operation.

When listed corn is to be cultivated, I avail myself of the fenders which have been shown in detail in Fig. 11 of the drawings. Said fenders, which are to be attached to the standards 64, consist of the inclined bearing-plates 68, having rearward-extending horizontal brackets 69 and 70, between which is pivoted a wing or plate 71. The latter is provided with a transverse bolt 72, upon which the fender-plate 73 is pivotally mounted. Said fender-plate, which is preferably constructed of sheet metal, is provided near its front end with a segmental slot 74, concentric with the bolt 72. Through said slot extends a transverse bolt 75, which also extends through the wing or plate 71. Upon the said bolt 75 is pivotally mounted a hand-lever 76, the front end of which is adapted to engage any one of a series of notches or recesses 77, formed in the under side of the arm or bracket 69. By this mechanism it will be seen that the fender-plate may be adjusted laterally to any desired angle with relation to the standard to which it may be secured. Vertical adjustment of the fender-plate may be had by loosening the nut upon the bolt 72, thus permitting the said plate to be tipped or tilted within the limits of the length of the slot 74.

78 designates the cultivator-tongue, which is secured by means of a vertical bolt 79 between the flanges 80, formed at the sides or ridges of a circular seat plate or disk 81. The latter is provided with downwardly-extending studs 82, working in segmental slots 83, formed in a circular disk or tongue-table 84, which latter is provided with downwardly-extending lugs, which are bolted or otherwise secured to the front and rear arched axle-bars 30. It will be seen that by this construction the tongue is connected pivotally with the axle-bars in such a manner as to be capable of swinging in a horizontal plane to an extent limited by the length of the slots 83. At the same time the connection of the tongue with the arched axle-bars is very firm and durable, and the said axle-bars are materially raised and strengthened by the said connection.

The cultivator-beams are provided with

hooks 86, by means of which they may be temporarily suspended from the arms or brackets 33, as will be seen in Fig. 1 of the drawings.

70

From the foregoing description, taken in connection with the drawings hereto annexed, the operation and advantages of my invention will be readily understood by those skilled in the art to which it appertains. My improved cultivator combines the advantages of the tongue or tongueless sulky. It secures an independent hitch or attachment of the draft without losing perfect control of the gangs. It provides for the attachment of the hitch to the point of the beam without the medium of doubletree. The gangs in operation move not only independently of each other, but move backward and forward in line of progression and always at the same 85 distance apart. There is no side draft, and consequently no drifting of the gangs side-wise. The machine may be turned in the shortest possible space, and cannot possibly fall down or become tangled in the operation. 90 The draft is perfectly equalized, and the gangs or beams are so constructed and arranged that they may be managed or manipulated very easily and conveniently.

The general construction, arrangement, and 95 combination of the parts of the invention are simple, durable, and inexpensive, and the machine embodying my improvements may be produced at a smaller expense and operated with better results than most machines 100 that are now on the market and in general use.

Having thus described my invention, I claim—

1. In a cultivator, the herein-described 105 movement-standards, each composed of two parts or plates provided with semi-cylindrical flanges, and coupling caps connecting the said parts and having bearings for the said flanges, substantially as set forth.

110

2. The combination of the standard-plates 2, having flanges 8, provided with notches 9, and provided with outward-diverging shoulders 4, having downward-extending plates 5, provided with rearward-extending brackets 115 6, and the coupling-caps provided with flanges forming bearings for the notched flanges 8, and provided with lugs 15 to engage the notches of said flanges, substantially as set forth.

120

3. In a cultivator, the combination, with the movement-standard, composed of two similarly-constructed parts 2, of the coupling-caps having laterally-extending brackets and provided with bearings for the semi-cylindrical flanges upon the parts 2 and the connecting-bolts, substantially as set forth.

125

4. The combination of the movement-standards, each composed of the parts 2, 2, having notched flanges 8, the coupling-caps having 130 arms or brackets 12, provided with slots 29, having V-shaped lugs 31, and the arched

connecting-bars 30, having V-shaped notches 32, substantially as and for the purpose set forth.

5. The combination, with the standards, 5 each composed of two similarly-shaped parts or sections having semi-cylindrical flanges, of the coupling-caps having forward and rearward extending arms, the connecting-bolts, and the arms or brackets interposed between 10 the rearward-extending arms of the lower coupling-caps and extended upward and rearwardly to support the cultivator-beams when lifted out of operation, substantially as set forth.

15 6. The combination of the movement-standards, each comprising two similarly-constructed parts or sections formed with shoulders to bring their lower ends out of contact with each other, with the coupling-caps forming 20 bearings for flanges formed upon the said standards, the bolts connecting the lower ends of the sections of the latter, and the draft-hooks having rearward-extending arms, one of which is mounted upon the said connecting-bolt and the other of which is formed 25 with a hook to engage a slot near the lower end of one of said standard-sections, substantially as set forth.

7. The combination of the movement-standards, 30 the coupling-caps having bearings in which the said standards may partially rotate, the draft-hooks connected to the lower ends of said standards, the rearward-extending supporting-bars, and the arched connecting-bars, substantially as and for the purpose set forth.

8. In a cultivator, the combination, with the movement-standards having diverging lower ends, of the connecting-bolts, the 40 sleeves upon the latter, the spindles provided at their inner ends with upward-extending brackets having vertical slots and provided with transverse slots or corrugations on their outer sides, and the adjusting-blocks mounted 45 upon the outer ends of the adjusting-bolts and having teeth or corrugations engaging those of the spindle-brackets, substantially as set forth.

9. The combination of the movement-standards, 50 the bolts extending through the lower ends of the parts or sections of said standards, the bracing-sleeves upon said bolts, the spindles provided at their inner ends with upward-extending arms having vertical slots 55 and transverse teeth or corrugations, the transversely-toothed adjusting-blocks having vertical flanges at their outer front edges, and the draft-bars mounted upon the outer ends of said bolts and bearing against said flanges, 60 substantially as set forth.

10. The movement-standards comprising the parts 2, having divergent plates 5, provided with vertical ribs or flanges on their outer sides, in combination with the coupling-caps, the connecting-bolts, the sleeves upon the latter, and the spindles having vertically-slot-

ted arms provided with flanges to engage the flanged divergent plates of the standards and their adjusting-blocks, substantially as set forth.

11. The combination of the movement-standards having the rearward-extending brackets 6, the coupling-caps, the arched connecting-bars, the upward and rearward extending arms 33, and the cultivator-beams 70 jointed universally to the brackets 6 and provided with hooks to engage the said supporting-arms 33, substantially as set forth.

12. In a cultivator, the combination of the movement-standards having rearward-extending brackets 6, provided with perforations 47, lugs 48, teeth 49, and annular bosses 46, with the coupling-plates 57, having notched bosses 56, bolt-holes 59 and 60, and provided in their meeting faces with vertical grooves 80 62, the connecting-bolts, the coupling-plates having clevises provided with vertical pins or bolts to engage the grooves or recesses 62, and the cultivator-beams secured to said coupling-plates, substantially as and for the purpose set forth.

13. The combination of the movement-standards, the spindles secured adjustably to the latter, the adjusting-blocks provided with vertical flanges at their outer front edges, the 95 arms secured to the outer sides of said adjusting-blocks and bearing against the flanges of the latter, said arms being provided with hooks at their rear ends, and the draft-bars connected adjustably to said arms, substantially as and for the purpose set forth.

14. The combination of the movement-standards, the coupling-caps having bearings in which the said movement-standards may partially rotate, the arched connecting-bars, 105 the disk or plate having downward-extending lugs bolted or otherwise suitably secured to said arched bars and provided with segmental slots, the disk or turn-table connected pivotally to the said circular disk, and having 110 downward-extending pins working in the segmental slots of the latter and upward-extending flanges, and the tongue mounted upon said disk or turn-table between the flanges of the latter, substantially as set forth. 115

15. The combination of the movement-standards, the coupling-caps having bearings in which said standards may partially rotate, the cultivator-beams connected to said movement-standards by universal joints, the arched 120 bars connecting the coupling-caps in which the movement-standards are mounted, the tongue connected pivotally with the arched connecting-bars, so as to be capable of a limited swinging movement in a horizontal plane, 125 and the draft-hooks connected independently to the movement-standards, substantially as and for the purpose set forth.

16. The combination of the frame, the cultivator-beams, the inclined plates secured to 130 the keys of said beams and having horizontal arms or brackets, and the wings mounted

pivots between said arms or brackets and carrying the fender-plates, substantially as set forth.

17. The combination of the inclined plates having the rearward-extending horizontal arms, the wings or leaves mounted upon pivotal bolts between said horizontal arms, the fender-plates connected pivotally to said wings and having segmental slots at their front ends, the bolts extending through said slots, and the levers mounted upon said bolts and engaging notches in the under sides of the upper horizontal brackets, substantially as set forth.

18. The combination, with a cultivator, of 15 a fender for listed corn, connected pivotally so as to swing in a vertical plane to a leaf or wing which is mounted to swing in a horizontal plane, and mechanism for retaining the said fender at any desired adjustment, 20 substantially as set forth.

In testimony that I claim the foregoing as my own I have hereto affixed my signature in presence of two witnesses.

FLOYD ELRAGE MONTGOMERY.
